United States Patent Office

Des. 199,540
Patented Nov. 10, 1964

199,540

PORTABLE LANTERN

Nolan K. Rhoades, Beloit, and Ralph T. Jacobsen, Stoughton, Wis., assignors to The Electric Storage Battery Company, Philadelphia, Pa., a corporation of New Jersey

Filed Nov. 18, 1963, Ser. No. 77,464

Term of patent 14 years

(Cl. D48—24)

FIG.1

FIG.2

FIG.3

FIG.6

FIG.4

FIG.5

FIG. 1 is a perspective view of a portable lantern showing our new design.

FIG. 2 is a side elevational view thereof.

FIG. 3 is a top plan view thereof.

FIG. 4 is a rear elevational view thereof.

FIG. 5 is a front elevational view thereof.

FIG. 6 is an enlarged cross-sectional view taken along the line 6—6 on FIG. 3 of the drawing.

The undisclosed side is substantially the same in appearance as the disclosed side.

We claim:

The ornamental design for a portable lantern, as shown and described.
